Primary Examiner — Cynthia Underwood(74) *Attorney, Agent, or Firm* — Margaret Polson; Oppedahl Patent Law Firm LLC(57) **CLAIM**

The ornamental design for an asymmetric double sided carabiner, as shown and described.

DESCRIPTION

FIG. 1 is a top plan view of an asymmetric double sided carabiner, the gate being in dotted line is for illustrative purposes only and forms no part of the claimed design.

FIG. 2 bottom plan view of FIG. 1.

FIG. 3 is a left side elevation view of FIG. 1.

FIG. 4 is a right side elevation view of FIG. 1.

FIG. 5 is a front side elevation view of FIG. 1.

FIG. 6 is a rear side elevation view of FIG. 1; and,

FIG. 7 top isometric view of FIG. 1.
